SHOETREE

Julius Gershune, Louisville, Ky.

Application August 21, 1933, Serial No. 686,081

2 Claims. (Cl. 12—128.1)

This invention relates to shoe trees, that is a device to be inserted in a shoe to prevent it from warping when same is not in use; to stretch the shoe and iron out any wrinkles that may have developed in same while wearing it; and thus prolong the fine appearance of the shoe, and provide more comfort to the user of same.

The objects of this invention are, first, to provide a shoe-tree, simple in construction, inexpensive to manufacture and convenient to use; second, to reduce the total number of parts to a minimum; and third, to provide the shoe tree with simple means for easily adjusting it so that it may be used on various sizes of shoes.

While the above are the primary objects, it is a further object of this invention to provide the shoe tree with an adjusting device which while simple in construction and inexpensive to manufacture, will not necessitate the expenditure of too costly die equipment for stamping out the parts of same. It is also intended that this adjustment device be used in other relations as well as for shoe trees and the like as described here.

It is still a further object of this invention to improve the toe body (the part which fits in the front end of the shoe) in usefulness, capability of being manufactured at a low cost, and in appearance.

Referring to the accompanying drawing which forms part of the following description:

Figure 1 is a vertical view of the shoe-tree (shown in full lines) with an outline of the toggle arms in position for adjustment (shown in dot and dash lines), and an outline of the shoe (shown in dotted lines);

Figure 2, a plan view of the shoe-tree with part torn away to expose detail of wall section;

Figure 3, a section on the line 3—3 of Figure 1;

Figure 4, an end view of the toe-body on line 4—4 of Figure 1;

Figure 5, a detail of member 3;

Figure 6, a detail section on the line 6—6 of Figure 5; and

Figure 7, a detail of member 2.

The toe-body 1, preferably made of cast aluminum, contains two slots 9 located in the extreme front portion, and a plurality of slotted holes 8, extending longitudinally and located in that part of arch of greatest curvature. The reason for slots 8 being located so is because when the toe-body 1 is compressed in the front end of the shoe, the tension caused in the shoe at the arch will cause the inner surface of the shoe to stand away slightly from the toe-body 1 at that part of

greatest curvature; resulting in slight air spaces. Therefore, the slots 8, being located in said portion of greatest curvature of arch, will not effect the shape or form effect given the shoe by the toe body 1. Another advantage resulting from the slots being located so, is the improved ventilation due to air being allowed thru said slots to the inside of the shoe where it is normally not in close contact with the toe-body 1.

This combination of slotted holes, arranged in the above described manner, results not only in the economical use of material, but provides the maximum ventilation in the shoe without sacrificing the shape or form effect given it by the toe-body 1. Also, a neat and ornamental appearance is given the shoe-tree by the above slot arrangement.

Another feature of the invention is the portion of the wall section 10. Altho the toe-body 1 may be made of any desired material, I prefer to make same of cast aluminum. In order to produce same at a low production cost, it must be of such form or shape to allow easy and rapid handling in molding at the foundry. Referring to Figure 4, it is seen that the surface 17 curves inwardly approximating the normal shape of the human foot. In molding for production of castings, the pattern must be of such shape or form to allow its withdrawal from the mold. It is evident that if the toe-body 1 were to be made of uniform wall thickness, it would necessitate the making of cores in order to mold same. I prefer to make the portion of the wall section 10 thicker (as shown in Figure 2). This feature of the invention makes possible the withdrawal of the pattern from the mold and eliminates the expense of making cores in the production of these castings.

The underside of the toe-body 1, at its rear end is provided with a lug 18. To the lug 18, one end of the arm 2 is hinged by means of a rivet 7. The other end of arm 2 is provided with a hole 14, in which a shoulder rivet 11 is rigidly secured (see Figure 3). The arm 3 is provided with an elongated slot 12 including a series of slotted notches 13. The shoulder rivet 11 is adapted to engage in said slots 12 and 13; at the same time holding the arm 3 between its head 6 and the side of arm 2 (see Figure 3).

The arm 3 is also provided with a bent portion 50 extending thruout the length of slot 12, and at a fixed distance W from the slots 13 (that is, from the center line of rivet 11 when seated in said slot 13). The rivet 11 is fixed in the arm 2 so that its distance X from edge 15 is less than 55

the distance W ; their difference being equal to or more than the distance V . The distance Y (from rivet 11 to edge 16) is made equal (or slightly less if allowance for clearance is made) to distance W . The distance Z (from rivet 11 to any part of edge between 15 and 16) is either equal to or less than the distance W ; their difference, however, being less than distance V .

It is thus seen from the above description that the edge 16 or any part of edge on arm 2 between 15 and 16 will contact the underside of bent portion 5 (when opposite to it) and prevent the shoulder rivet 11 from leaving the slot 13 . (See Figure 3.) However, by holding the toggle arms 2 and 3 in position indicated by dot and dash lines (see Figure 1), the edge 15 will then be brought opposite the underside of bent portion 5 ; and since $W-X$ is equal or greater than V , the rivet 11 , will in this position be allowed to leave the slot 13 and enter the elongated slot 12 , in which it may be moved along and be inserted in any of the slots 13 . The foregoing arrangement enables one to vary the effective length of the toggle arm 3 as desired, and to hold the two toggle members in a pivotal and adjusted position; thereby, permitting the shoe-tree to be used for various shoe lengths.

In using the shoe-tree, the toe-body 1 is inserted inside the front end of the shoe; the toggle arms 2 and 3 held in position indicated by dot and dash lines (see Figure 1); the pivot 11 is inserted in one of the slots 13 (selecting the one to suit the size of the shoe used); then the toggle arms 2 and 3 are pushed downwards (by means of pressure by hand exerted on bent portion 5); thus causing the toe-body 1 to be pushed inside the front end of the shoe, and the heel body 4 to be pushed against the inside of the rear end of the shoe; and stretch the shoe in a lengthwise direction. The downward movement of the toggle joint being limited by edge 16 in contact with bent portion 5 , the toggle arms 2 and 3 will come to a stop when they have reached the position shown in full lines in Figure 1. In this position, pivot 11 is off center below the line of thrust, and the toggle members 2 and 3 will remain in their locked positions.

The foregoing is a description of a single specific embodiment of my invention which best illustrates it. However, there may be modifications in the construction of several parts and in the arrangement of same. For instance;

The toe-body 1 may comprise a combination of two or more parts; or it may be modified in construction; or it may be made of wood or a different material than indicated by the above description.

The slots 12 and 13 may be incorporated in the

toggle arm 2 ; and the edge 15 and 16 with pivot 11 in the toggle arm 3 .

The slots 12 and 13 , or inversely, the edges 15 and 16 with pivot 11 , may be incorporated in the toe-body 1 ; thus eliminating one of the toggle arms entirely.

The elongated slot 12 may be eliminated leaving the slots 13 as notches in one of the members, and other means than slot 12 (within the scope of this invention) provided to prevent complete separation of members.

The pivot 11 may be an integral part of one of the members, or may be eliminated entirely; substituting other means of hinging or connecting members (within the scope of claims for this invention).

The heel-body 4 , as shown (see Figure 5), is formed integrally with the arm 3 by bending to shape and twisting it; the outside surface being curved inwards (see Figure 6) to prevent edges from making an imprint on or tearing the lining of the shoe. While this is one of the features of the invention, the heel body 4 , may however, be made of wood if desired, and attached to the toggle arm 3 .

The two slots 9 in the extreme front end of the toe-body 1 may be replaced by a single slot.

Having thus described my invention and apparent modifications of same, I claim:

1. An adjustment device consisting of two members; one of said members provided with a curvilinear end section and a pivot; said pivot adapted for selectively engaging one of a plurality of branching slots of an elongated slot contained in the other member; and a portion of said other member adapted to abut a portion of said curvilinear end section for the purpose of confining the pivot in the selected branching slot.

2. A toggle joint consisting of a pair of toggle arms; one of said toggle arms provided with a curvilinear end section and a pivot; said pivot adapted for selectively engaging one of a plurality of branching slots of an elongated slot contained in the other toggle arm for obtaining adjustment between said toggle arms; a portion of said other toggle arm adapted to abut said curvilinear end section for the purpose of confining the pivot in the selected branching slot; said portion of said other toggle arm adapted to abut a portion extending from one extremity of said curvilinear section for the purpose of locking said toggle arms in any one of their adjusted positions; and said portion of said other toggle arm adapted to abut a portion of the other extremity of said curvilinear section for the purpose of permitting said pivot to be released from the selected branching slot.

JULIUS GERSHUNE.
